UNITED STATES PATENT OFFICE

JOHN C. RAMSEY, OF SUFFOLK, VIRGINIA, ASSIGNOR TO RAMSEY PACKAGE CORPORATION, OF SUFFOLK, VIRGINIA, A CORPORATION OF VIRGINIA

BARREL FORMING MACHINE

Application filed October 18, 1927. Serial No. 226,949.

My invention relates to barrel forming machines and more particularly to that type of machine wherein the barrel is formed from a plurality of staves held together by 5 hoops or bands.

An object of this invention is to provide a barrel forming machine wherein the staves may be readily placed in proper formation and securely held until the hoops or other 10 retention means are applied.

Further the invention provides a barrel forming machine embodying a collapsible form or mandrel whereby the completed barrel body may be removed with facility 15 and ease, the form or mandrel being manually collapsible for this purpose.

Still another object of the invention resides in the provision of a barrel forming mandrel which is rotatable step by step to 20 facilitate placing of the staves thereon.

With the preceding and other objects and advantages in mind, the invention consists in the novel combination of elements, constructions and arrangements of parts to be 25 hereinafter specifically referred to, claimed and illustrated in the accompanying drawings, wherein:

Figure 1 is a front elevation of the machine;

30 Figure 2 is a rear elevation of the same; Figure 3 is an end elevation;

Figure 4 is a view similar to Figure 3 but showing the reverse end of the machine; and

Figure 5 is a transverse sectional view 35 taken on line 5-5 of Fig. 1.

Referring to the invention in detail a rectangular frame 5 is provided which includes vertical supporting legs 6.

A collapsible or barrel form is provided 40 which includes a shaft 7 extending longitudinally and horizontally within the frame and supported in bearings 8. As illustrated in Figures 1 and 4, the forward end of this shaft carries a spider 3 of cruciform configuration having pairs of parallel arms 9.

To support barrel staves in position to form a barrel, a series of transversely curved and longitudinally bowed segments 10 having normally abutting bevelled longitudinal edges 11 as illustrated in Figure 5, extend 50 circumferentially around the shaft.

At their forward ends each of the segments is formed with a pair of parallel arms 12 which converge towards the front edge of the shaft and are pivotally connected to the parallel arms of the spider by pivot pins 13 passing through each pair of the latter arms and the arms 12.

For the purpose of collapsing the form a pair of H-shaped levers 14, each disposed 60 upon opposite sides of the shaft intermediate the ends of the segments, are pivotally connected together at their inner ends by means of a pivotal element 16 and to a collar 21 which is engaged by a yoke 15 by which it is 65 slid on the shaft. The outer ends of these levers are pivotally connected with parallel ears 17 formed upon the inner faces of two diametrically opposite segments.

To shift the yoke to collapse the form a 70 horizontally disposed hand lever 18 is pivotally mounted upon a laterally projecting bracket 19 attached to the frame adjacent one end thereof. An actuating rod 19' extending longitudinally of the form has one end pivotally 75 connected to the hand lever and its opposite end operatively connected with a rectangular body 20 which in turn is rigid with the yoke 15.

Disposed upon opposite sides of the shaft 80 and projecting laterally from the inner face of the other pair of diametrically opposed segments are slotted brackets 23 which receive oppositely extending stop blades 24 projecting from the collar 21. A pair of parallel 85 contractile springs 25 are connected to this pair of diametrically opposed segments and normally draw the latter together. It will be observed that when the form is collapsed 90 the end walls of the slotted brackets engaging

the ends of the stop blades will limit the inward movement of the resiliently connected pair of segments.

The invention contemplates means for temporarily securing staves from which the barrel is formed to the form until the securing hoops have been placed on the staves. This means consists of a shaft 29 extending longitudinally of the form and journaled in bearings 30 one on one side thereof and carrying pulleys 31 which are located at the ends of the form. A crank handle 32 is carried by one end of the shaft for rotating the latter while a ratchet wheel 33 is also fixed to this end of the shaft and held against rotation in one direction by a pawl 34 projecting laterally from the frame. Flexible elements 35 are attached to the rear side of the frame below the form as at 36, and are extended circumferentially about each end of the form to engage the ends of the staves placed thereon, then wound about the pulleys 31 and finally fastened to said pulleys. A second pair of flexible elements 38 are trained over pulleys 39 mounted upon the upper face of the frame at the rear thereof at points equidistant from the ends of the form. These flexible elements 38 carry weights 40 at one end while their opposite ends are secured to a channel shaped securing bar 41 adapted to be received on the upper ends of angle brackets 42 attached to the upper face of the frame. The flexible elements 38 extend from the channel bar 41 downwardly under the form and then upwardly over the pulleys 39 and are maintained in engagement with the form by the tensioning effect of the weights 40. In this connection, it will be observed that regardless of the size of the form or the thickness of the staves, the flexible elements 38 will always be maintained in engagement with the under side of the form or with the staves placed thereon.

Barrel staves, before assembling to provide a barrel, are perfectly flat and to bow these staves transversely while on the form, a die 44 is provided. This die comprises a pair of longitudinally curved arms 45 connected intermediate their ends by a bar or brace 46. As illustrated in Figure 4, these arms extend transversely of the frame and have their rear ends pivoted to brackets 47 attached to the frame. A hand lever 48 also pivotally mounted on the frame adjacent the bracket 47 is rigidly connected with the arms by means of straps 49. With several staves placed upon the form the die is brought to bear upon the staves and shape them to the cross sectional area of the form by exerting manual down-pressure upon the hand lever 48.

For the purpose of correctly positioning the staves on the form, an upwardly extending longitudinally curved gage element or blade 50, attached to the frame, extends along

the inner edge of the form against which the inner ends of the staves engage when slipped longitudinally into position.

Means is provided for rotating the form step by step to expose an uncovered area of the same at the top, so that the staves can be laid on the form said means comprising a ratchet wheel 51 fixed to one end of the shaft 7 and engageable by a pawl or hook 52 formed upon the upper end of a vertically movable lever 53, the latter being pivotally connected to an arm 54 fixed to a horizontally extending rock shaft 55 journaled in the frame. A treadle or foot engaging element 56 fixed to the rock shaft is provided for moving the lever 53 downwardly to successively engage the teeth of the ratchet wheel and thereby rotate the former. A contractile spring 57 has one end connected with the lever 53 and its opposite end connected with the frame 5 for normally returning this lever to raised position.

With my invention it will be observed that the staves are retained on the form of a barrel by means of the flexible element passing around the staves until hoops or other permanent fastenings are slipped over the staves and secured. The flexible elements are now disengaged by slackening the same and the form then collapsed to permit the complete article to be removed.

In the operation of the machine the barrel staves are successively laid on the form at that side nearest the angle bracket 42. As each stave is placed on the form it is rotated a partial revolution and the next stave laid in place. As the form is rotated the staves are held between the flexible elements 38 and the periphery of the form. It will be observed that it will be unnecessary to hold the staves on the upper portion of the drum or that part not embraced by the cables 38 as they will lie in place. The cables 35, which have been previously slipped off the ends of the drum are now slipped back on and then drawn taut by rotation of the handle 32. These cables 35 securely hold the ends of the staves until hoops have been inserted on the form and secured to the staves. When it is desired to remove the completed barrel the members 41 are disengaged from the brackets 42 to allow the cables 38 to depend and the cables 35 slackened and slipped over the ends of the drum. The form is then collapsed and the barrel slipped longitudinally therefrom.

What is claimed is:

In a barrel forming machine, a support, a collapsible mandrel supported thereon, a plurality of flexible elements underlying the mandrel, pulleys supported to one side of the mandrel and over which one end of the flexible elements are trained, weights attached to the depending ends of such flexible elements, upstanding plates attached to the support at the opposite side of the mandrel, and a chan-

nel-shaped securing member carried by the opposite end of each of the flexible elements and removably engaged with one of the up-standing plates whereby the flexible elements
5 take a substantial U-shaped form to constitute cradle-like temporary supports for staves placed on the mandrel, and means for securing the ends of the staves to the mandrel until hoops have been secured on such
10 staves.

Signed at Suffolk, in the county of Nance-
mond, and State of Virginia, this 15th day of
October A. D. 1927.

JOHN C. RAMSEY.
